UNITED STATES PATENT OFFICE

SIGURD A. SOLLIE, OF PALO ALTO, CALIFORNIA, ASSIGNOR TO FEDERAL TELEGRAPH COMPANY, OF SAN FRANCISCO, CALIFORNIA, A CORPORATION OF CALIFORNIA

SOUND REPRODUCER

Application filed January 21, 1928, Serial No. 248,403. Renewed August 2, 1929.

My invention relates broadly to electro-magnetic sound reproducers and more particularly to a sound reproducer of the conical diaphragm type.

One of the objects of my invention is to provide a method of supporting an armature coil with respect to a conical shaped sound reproducing diaphragm by which sound vibrations may be imparted to the diaphragm uniformly at a section thereof.

Another object of my invention is to provide a construction of armature member for a conical shaped sound reproducing diaphragm wherein a rigid connection may be made between the sound reproducing diaphragm, the suspension means therefor and the support for the armature coil.

Still another object of my invention is to provide a construction of support for an armature winding for driving a conical shaped sound reproducing diaphragm, wherein the sound reproducing diaphragm extends into an annular channel formed in the support and into which the suspension means for the sound reproducing diaphragm is also arranged to extend.

Other and further objects of my invention will be understood from the specification hereinafter following by reference to the accompanying drawing, in which:

Figure 1 is a side elevation of the sound reproducing diaphragm partially broken away and showing the armature member in cross section; Fig. 2 is an enlarged cross-sectional view through the armature member showing the suspension means and cone in the process of being applied to the armature member. Fig. 3 is a cross-sectional view of the armature member and suspension means secured to the cone diaphragm; and Fig. 4 is a plan view of the suspension means employed in the sound reproducer of my invention.

My invention is directed to that class of sound reproducing diaphragm set forth more particularly in the Kolster-Sollie United States Patent No. 1,637,119, dated July 26, 1927. The suspension means employed in the sound reproducer of my invention is more clearly set forth in copending application Serial No. 224,738, filed January 5, 1928.

By my invention, I provide a simplified method of assembly for the armature winding support and the cone and suspension means whereby the manufacture and production of the sound reproducer may be carried on with greater economy and the manufacturing processes rendered more practical.

Referring to the drawing in detail, reference character 1 designates the sound reproducing diaphragm which is substantially in the shape of the frustum of a cone terminating in an annular section at the raw edge 2. The winding support is designated at 3 in the form of an insulated tube having a groove 4 formed therein to receive an armature winding and a groove 5 formed therein to receive the raw edge 2 of the cone. An armature winding 6 is found between the annular walls 7 and 8 formed on the tubular member 3. The end wall 9 of the tubular member 3 is substantially conical shaped at 10 to conform with the pitch of the cone shaped diaphragm 1. The suspension means for the diaphragm is formed from a resilient metal spider represented at 11 having arms 12 and an annular extension 14 thereon. The annular extension 14 is shown in Fig. 2 preparatory to an operation by which the cone 1 is rolled into the groove 5 of the armature member 3.

In Fig. 3, the cone 1 is shown completely rolled into the groove 5 and rigidly anchored in place by the annular portion 14 of the spider 11. The vibration of the outer peripheral edge of the cone shaped diaphragm 1 is damped by means of the annular strip 16, which is secured between the sections 17 and 18 of the frame of the cone. An angularly disposed wall 19 extends from the frame 18 and from this wall the arms 20 protrude to points upon plate member 21 of the electrodynamic driving unit. The driver for the cone includes a field winding 22, casing 23, and central pole piece 24 arranged to provide an annular gap 25 in which the armature support 3 is centered. Pedestals 26 extend from plate 21 for supporting the spider 11 in such position that winding 6 is suspended within the gap 25.

The method of forming the sound reproducing diaphragm interlocked with the arma-

ture tube has been found to be extremely practical and desirable in construction, and while I have described one of the preferred embodiments of my invention, I desire that

5 it be understood that modifications may be made and that no limitations upon my invention are intended other than are imposed by the scope of the appended claims.

10 What I claim as new and desire to secure by Letters Patent of the United States is as follows:

1. In a sound reproducer, a conical shaped sound reproducing diaphragm, a cylindrical supporting member carrying a winding, said 15 cylindrical supporting member having an annular groove formed therein, and a resilient suspension member conforming to the contour of said conical shaped sound reproducing diaphragm and providing an anchoring 20 means for locking said conical shaped sound reproducing diaphragm within said groove and said cylindrical support.

2. In a sound reproducer, a sound reproducing diaphragm substantially in the form 25 of a frustum of a cone, a cylindrical coil support having an annular groove formed therein, a resilient suspension member embracing said conical shaped sound reproducing diaphragm and having a portion thereof extending parallel to the surface of said sound-reproducing diaphragm and protruding into said annular groove in said cylindrical coil support for anchoring said conical shaped diaphragm with respect to said cylindrical 30 coil support.

3. In a sound reproducer, a sound reproducing diaphragm substantially in the form 40 of a frustum of a cone, a cylindrical coil support projecting through one end of said sound reproducing diaphragm having an annular groove formed therein for receiving the annular extremity of said conical shaped sound reproducing diaphragm, a suspension member embracing said conical shaped sound 45 reproducing diaphragm and providing a sealing means for the extremity of said conical shaped sound reproducing diaphragm within said annular groove for establishing a rigid connection between said conical shaped sound 50 reproducing diaphragm and said cylindrical coil support.

4. A sound reproducer comprising a sound reproducing diaphragm substantially in the form of a frustum of a cone, a cylindrical coil support projecting through one end of said sound reproducing diaphragm, said cylindrical coil support having an annular groove adjacent one end thereof, one side of said groove forming an abutment for the edge 60 of said conical shaped sound reproducing diaphragm, and the other wall of said groove conforming to the pitch of said sound reproducing diaphragm, and suspension means embracing said diaphragm in a position intermediate the peripheral edges thereof, said

suspension means extending into the annular groove on said cylindrical coil support and providing means for locking said diaphragm within said groove.

5. In a sound reproducer, a sound reproducing diaphragm substantially in the form 70 of a frustum of a cone, a cylindrical coil support extending through one end of said diaphragm and having an annular groove formed in the surface thereof, one end of said groove 75 providing an abutment for the peripheral edge of said diaphragm, and the other end of said groove being shaped to conform to the pitch of said diaphragm, and a suspension member embracing said diaphragm and conforming to the shape thereof, said means abutting against one wall of said groove and uniting said diaphragm with said cylindrical coil support.

6. In a sound reproducer, a sound reproducing diaphragm substantially in the form 80 of a frustum of a cone, a coil support projecting through one end of said diaphragm, said coil support having a flange formed thereon providing an abutment with the edge 85 of said diaphragm, and a suspension member embracing said diaphragm and conforming to the shape thereof, said suspension member having its edge abutting with the flange on said coil support and extending immediately adjacent the surface of said diaphragm for uniting said diaphragm with respect to said coil support.

7. In a sound reproducer, a sound reproducing diaphragm substantially in the form 100 of a frustum of a cone having an annular extremity, a cylindrical coil support projecting through one end of said sound reproducing diaphragm and receiving the annular extremity of said conical shaped sound reproducing diaphragm, a suspension member embracing said cylindrical coil support and also the conical extremity of said sound reproducing diaphragm next to said annular extremity, thereby establishing a rigid connection between 105 said conical shaped sound reproducing diaphragm and said cylindrical coil support.

8. In a sound reproducer, a conical shaped sound reproducing diaphragm, a cylindrical supporting member carrying a winding and 115 having an annular groove formed therein, a resilient suspension member a portion of which conforms with the conical surface of said sound reproducing diaphragm, said member providing locking means whereby a 120 portion of said sound reproducing diaphragm is anchored within said groove.

9. A coil mounting for cone speakers comprising a cylindrical member adapted to be secured to the apex of a cone and support a 125 current-carrying winding, and a flat flexible supporting member extending from said cylindrical portion adapted to engage fixed supports, said supporting member being secured upon said cylindrical portion intermediate 130

the ends thereof by disposing it against a shoulder upon said cylindrical member, the projecting end of the cylindrical member flaring outwardly against said flexible member opposite said shoulder.

- 5 10. A support for the coil-carrying end of loud speaker cones comprising a cylindrical member adapted to be secured to the apex of the cone and support a current-carrying winding, a flat flexible member projecting outwardly from the surface of said cylindrical member, and means for securing said flexible member to said cylindrical member consisting of a shoulder formed upon said cylindrical member contacting with one side of said flexible member, said cylindrical member flaring against said flexible member opposite said shoulder.

In testimony whereof I affix my signature.
